UNITED STATES PATENT OFFICE.

GLENN CHARLES BROWN, OF BESSEMER, ALABAMA.

ROPE-THIMBLE.

No. 857,717.

Specification of Letters Patent.

Patented June 25, 1907.

Application filed March 16, 1906. Serial No. 306,468.

To all whom it may concern:

Be it known that I, GLENN CHARLES BROWN, a citizen of the United States, residing at Bessemer, in the county of Jefferson and State of Alabama, have invented certain new and useful Improvements in Rope-Thimbles; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to "thimbles" designed to be used particularly for wire rope, and my invention has for its object to provide a thimble which can be easily applied to the rope and wherein the rope can be 20 constantly inspected in order to detect any probable weakness.

A further object of my invention is to provide a thimble which is practically non-breakable, but is strong, durable and efficient.

25 A further object of my invention is to provide a thimble with which either an old or new rope may be employed without affecting the strength of either.

With these objects in view, my invention 30 consists in the novel construction of the thimble and in certain combinations of parts which will be first fully described and afterward specifically pointed out in the appended claims.

35 Referring to the accompanying drawing. Figure 1 is an elevation of thimble showing rope in position and rope-clamp. Fig. 2 is a vertical transverse section taken on line 2—2 of Fig. 1. Fig. 3 is an end elevation of the 40 wedge member and clamps, and Fig. 4 is a vertical transverse section taken on line 4—4 of Fig. 1.

Like numerals of reference indicate the same parts throughout the several figures in 45 which:

1 indicates the device which comprises the thimble 2, wedge member 3, keys 4 and transversely adjustable clamps 5.

Referring to Figs. 1 and 2 it will be seen 50 that each of the inner edges 6 of the thimble 2 is provided with a sharp longitudinal groove 7, and that the upper and lower edges 8 of the wedge member 3 are provided with a double bevel to conform to said grooves 7.

55 Referring to Figs. 1 and 4 it will be seen

that two keys 4 are passed through openings made transversely through the thimble 2 and wedge member 3, said keys 4 engaging the inner edges of the thimble and the outer edges of the wedge member 3 in the manner 60 as shown in Fig. 1 in order to effectually key or lock the two parts together.

The wedge member 3 is provided with a series of bolt holes 10 through which the bolts 11 pass to secure the clamps 5 in position; 65 said bolts passing through said clamps and being provided with suitable nuts and jam nuts 12 and 13 or any other convenient means for securing the clamps.

As shown in Figs. 1, 2 and 3 the thimble 2 70 and wedge member 3 are provided on their outer edges with a concaved groove in order to accommodate the rope 14, the wedge member 3 tapering until the grooves on each side thereof meet at the end 15 as shown in Fig. 3. 75

Having thus fully described the several parts of my invention, its operation is as follows: In order to assemble the parts for operation, the thimble 2 is placed over a clevis or other element to which the thimble is to be 80 connected, and the wedge member 3 is inserted in the thimble, and the keys 4 are driven in position. The rope is then drawn around the thimble and wedge member plenty of end length being given so that a 85 substantial end is left at the end of the wedge member, and one or more suitable rope clips 16 applied about the rope: any approved type of rope clip being employed. The clamps 5 are then placed in position and the 90 nuts carried down hard to draw the two sides of the clamps together; the ends 17 of the clamps being curved or bent inwardly in such manner that the rope is almost entirely surrounded thereby. The clamps being thus in 95 position the thimble and rope is ready for operation.

Having thus fully described my invention I do not wish to be understood as limiting myself to the exact construction herein set 100 forth as various slight changes may be made therein which would fall within the limit and scope of the following claims.

What I claim as my invention and desire to secure by Letters Patent of the United 105 States is:

1. In a device of the character described, the combination of a thimble, a wedge member constructed to be inserted in said thimble, a suitable key for locking said thimble 110

and wedge member together and a clamp constructed to engage the rope, said clamp being carried by said wedge member, substantially as described.

5 2. In a device of the character described, the combination of a thimble, a member constructed to be inserted in said thimble, means for locking said thimble and member together, and a clamp associated with said

thimble and member for engaging the rope, substantially as described.

In testimony whereof, I affix my signature, in presence of two witnesses.

GLENN CHARLES BROWN.
